DEFLECTOR FOR A GARDEN SPRAYER OR SIMILAR ARTICLE

John D. Beinert, Babylon, N.Y., assignor to International Patent Research Corp., New York, N.Y., a corporation of New York

Filed Dec. 10, 1963, Ser. No. 77,738

Term of patent 7 years

(Cl. D31—3)

FIG. 1

FIG. 2

FIG. 5

FIG. 4

FIG. 3

FIG. 8

FIG. 7

FIG. 6

FIG. 1 is a perspective view of a deflector for a garden sprayer or similar article showing my new design, the broken line representation of the sprayer unit being shown for illustrative purposes only;

FIG. 2 is a side view thereof, with the deflector in an alternate position, the broken line representation of the sprayer unit being shown for illustrative purposes only;

FIG. 3 is an end elevation as seen from the right of FIG. 2 with the deflector rotated 90° counter clockwise;

FIG. 4 is a side elevation as seen from the left of FIG. 3;

FIG. 5 is an end elevation as seen from the left of FIG. 2 with the deflector rotated 90° counter clockwise;

FIG. 6 is a side elevation as seen from the right of FIG. 3;

FIG. 7 is a side elevation as seen from the bottom of FIG. 3; and

FIG. 8 is a side elevation as seen from the top of FIG. 3.

The dominant portions of the design are shown in solid lines.

I claim:

The ornamental design for a deflector for a garden sprayer or similar article, as shown and described.
